UNITED STATES PATENT OFFICE.

EDMOND W. T. RICHMOND, OF ROMFORD, ENGLAND.

DESIGN FOR A GAS-STOVE.

SPECIFICATION forming part of Design No. 33,969, dated January 22, 1901.

Application filed December 26, 1900. Serial No. 41,169. Term of patent 14 years.

To all whom it may concern:

Be it known that I, EDMOND WALTER TYRRELL RICHMOND, a subject of the Queen of Great Britain, residing in Summereourt, Romford, in the county of Essex, England, have invented and produced a new and original Design for Gas-Stoves, of which the following is a specification.

The accompanying drawing is a perspective view of a gas-stove embodying my design.

The leading features of my design are the rectangular body portion A, having the flat top a, which supports open-work standards B, on which is a frame C, supporting a series of parallel bars D, the coupling E, arranged at one side of one of the standards, and above which there is a series of cock-handles F, the panel G at the front of the body portion, the

horizontal hinge members H, and the latch I, the inner end of which extends between the hinge members.

On each side of the front of the body portion there are pilasters ornamented by panels e, having vertical corrugations. The central panel G is also ornamented by vertical corrugations, and above and below the latch in the panel G are circular figures g.

I claim—

The design for a gas-stove, substantially as herein shown and described.

In testimony whereof I have hereunto subscribed my name.

EDMOND W. T. RICHMOND.
